UNITED STATES PATENT OFFICE

164,224

TOY MONEY BANK

Dominic A. Di Camillo, Fairfield, Conn.

Application July 19, 1949, Serial No. 3,990

Term of patent 7 years

(Cl. D34—11)

To all whom it may concern:

Be it known that I, Dominic A. Di Camillo, a citizen of the United States, residing at Fairfield, county of Fairfield, and State of Connecticut, have invented a new, original, and ornamental Design for a Toy Money Bank, of which the following is a specification, reference being had to the accompanying drawing, forming part thereof.

Fig. 2 is a side elevation of the bank shown in Fig. 1 viewed from the right;

Fig. 3 is a top view of the bank shown in Fig. 1;

Fig. 4 is a rear elevational view of the bank shown in Fig. 1; and

Fig. 5 is a side elevation of the bank shown in Fig. 1 viewed from the left.

The characteristic feature of my design resides in the wide doors having an arched cap located in the front end of the wing and positioned under the overhang of the roof.

I claim:

The ornamental design for a toy money bank, substantially as shown and described.

DOMINIC A. DI CAMILLO.
